(57) **CLAIM**

The ornamental design for a “multi-function container lid with integrated knife or straightedge cleaner” as shown and described.

DESCRIPTION

FIG. 1 is a perspective view of a multi-function container lid with integrated knife or straightedge cleaner shown in a first configuration;

FIG. 2 is a perspective view thereof in a second configuration with an upturned tab;

FIG. 3 is a perspective view thereof in a third configuration with an upturned cleaning plate;

FIG. 4 is a perspective view thereof in a fourth configuration that has an upturned cleaning plate and tab;

FIG. 5 is a top perspective view thereof shown in a fifth configuration in an unfolded state;

FIG. 6 is a bottom perspective view thereof;

FIG. 7 is a top plan view thereof; and,

FIG. 8 is a bottom plan view thereof.

1 Claim, 6 Drawing Sheets
